UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

FILLED-BAG-SEWING APPARATUS.

1,303,121.

Specification of Letters Patent.

Patented May 6, 1919.

Application filed March 10, 1911. Serial No. 613,583.

To all whom it may concern:

Be it known that I, DUDLEY S. SEYMOUR, a citizen of the United States, residing at Oak Park, in the county of Cook, State of Illinois, have invented certain new and useful Improvements in Filled-Bag-Sewing Apparatus, of which the following is a description, reference being had to the accompanying drawing, and to the letters and figures of reference marked thereon.

My invention relates to an improvement in filled bag feeding and sewing apparatus, as ordinarily constructed as shown for example in my application for patent filed January 6th, 1910, Serial No. 536,765; and in the patents granted John Bigelow, and C. H. Foster, December 31st, 1907, numbered respectively 875,314 and 875,339, these apparatus including a supporting framework, an overhanging frame supporting a sewing head and a vertically adjustable conveyer table, over which runs a belt to deliver the bags to the sewing mechanism. If desired too, the sewing head may be made adjustable vertically. In an apparatus of this character, the conveyer is on the supporting framework, and the filled bags to be sewed must be placed by an operator on said conveyer.

In some factories where large sacks or bags are to be filled and sewed, an independent conveyer of considerable length is sometimes used, which passes in front of the packing apparatus, and when filled is placed upon this conveyer and carried toward the bag sewing apparatus. In such an arrangement, it is difficult to cause the bags to pass from the one conveyer to the conveyer which forms a part of the bag sewing apparatus; hence an operative must stand beside the sewing machine to help the bags from one conveyer to the other.

It is the object of the present invention to adapt the sewing apparatus for use in connection with a conveyer which is independent thereof, and which may be of any suitable length and adapted to convey the largest sizes of filled sacks to the sewing apparatus, without necessitating their handling from the time they are packed until they are sewed.

In an apparatus of this character, the top of the conveyer is usually in a plane coincident with the plane of the floor. It is desirable to provide means whereby the con-

veyer can be operated without the necessity of operating the sewing machine, for the reason that when large bags are sewed if there were considerable space between two consecutive bags, the consumption of thread in chaining between them would be wasteful.

When the sewing machine however, is operating upon a bag fed along by the conveyer, the top of the sack must be fed along at the same rate of speed by the feed of the machine, as the body of the bag is fed along by the conveyer.

My invention therefore, comprises a conveyer and means for operating it, and a sewing mechanism carried on a framework overhanging the conveyer, with means for operating them in unison or one of them independently of the other, said means for operating them including a common motor, or independent motors, with clutches controlling the transmission of the power between them, the motor or motors, and the conveyer and sewing mechanism, there being provided two treadles or other means of control, which may be operated either to simultaneously throw the devices into operation, or to operate one device independently of the other.

Further the invention consists in the matters hereinafter described and referred to in the appended claims.

The invention is illustrated in the accompanying drawings in which;

Figure 1 is a side elevation of an apparatus constructed in accordance with my invention;

Fig. 2 is a plan view; and
Fig. 3 an end elevation.

In these drawings; The large conveyer is shown at 1. It may be of considerable length, forty feet more or less, and is arranged adjacent the packing stand, so that the bags when filled may be placed therein and carried to the stitching mechanism. Such a conveyer when used for large sacks, is preferably arranged so that its upper travel is at the floor line, so that the bags will not have to be lifted.

It is trained over rollers 2, journaled in bearing standards 3. It is operated by an electric motor 4, the shaft of which 5 has a clutch connection 6, with the shaft 7, carrying near its opposite end, the worm gear 8, meshing with the worm wheel 9, on

the shaft 10, which shaft also carries one of the rollers 2.

The clutch 6 is controlled by the treadle 11, which is attached to the long lever 12, 5 pivoted at its opposite end to one arm of a bell crank lever 13, pivoted to a bracket 14 on the frame of the apparatus, the other arm 15 of the bell crank, engaging the clutch in the usual manner.

10 The movement of the conveyer is thus controlled by the treadle 11. The sewing apparatus and its supporting framework need not be specifically described, since they are the same as illustrated in my application 15 for Letters Patent, filed January 6th, 1910, Serial No. 536,765. The sewing head is adjustable for the accommodation of the different sizes of sacks, and to regulate if desired, the position of the line of stitching 20 in the bag mouth.

The sewing mechanism is operated from an electric motor 16, through the connections shown, a clutch 17 controlling the operation of said connections. The pivoted 25 lever 18 operating the clutch, is attached to the connecting rod 19, and at its lower end is attached to an arm 20 on the horizontal rod 21, extending to the front of the machine, and connected at its outer end to the 30 arm 23 supporting the treadle 22. The treadle 22 controls the operation of the sewing mechanism. It will thus be seen that the conveying mechanism may be operated independently of the sewing mechanism, and 35 the latter may remain stationary, which is an advantage in the saving of thread in avoiding long chains between sacks if they are considerably spaced apart on the conveyer.

40 While it is desirable that the conveyer should operate at times without the sewing mechanism operating, it is also desirable that when the sewing mechanism is thrown into action, the conveyer belt should practically be started automatically as the feed of the sewing machine itself obviously can not feed the sack. Therefore, as a further and special improvement in apparatus of this character, I have arranged the lever 23 45 of the sewing mechanism treadle, to cross over the lever 12 of the conveyer mechanism treadle, whereby when the treadle 22 is depressed, its downward movement will depress the treadle 12, thus starting the conveyer or maintaining it in operation, if it has previously been in operation by depression of the treadle 12.

46 The clutch for the sewing mechanism and also the clutch for controlling the conveyer 60 belt are each of the usual construction wherein a spring normally holds the clutch members separated. The operator upon depressing the treadle overcomes the action of the clutch members. When, however, the 65 treadles are released the springs will at once

separate the clutch members and raise the treadles.

Any other means for the successive operation of the two treadles may be substituted, such as other connections between the 70 treadle levers, or the operative's foot may bridge both treadles. In this way, the sewing machine and conveyer may be operated together, or the conveyer independently of the sewing machine by moving the toe of 75 the foot from one treadle to the other, the weight of the body resting upon the other foot and the heel.

As above stated, the feed of the sewing machine should move the bag mouth at the 80 same speed as the conveyer belt moves the sack body.

Having thus particularly described my invention, what I claim as new and desire to 85 secure by Letters Patent, is:—

1. An apparatus of the character described, a conveyer, an operating means for the conveyer including a clutch, a sewing mechanism, an operating means for the sewing mechanism including a clutch and means 90 for controlling the clutches of the sewing mechanism operating means and the conveyer operating means, said controlling means including devices disposed relative to each other for jointly operating both of the 95 clutches and whereby one of the clutches may be operated independently of the other clutch.

2. An apparatus of the character described, a conveyer, means for operating the 100 conveyer, including a clutch, a sewing mechanism supported in proper coöperative relation to the conveyer to sew the mouths of sacks supported and carried by said conveyer, means for operating said sewing 105 mechanism including a clutch, controlling means for operating the clutches including treadles so disposed relative to each other that said treadles may be operated together, for starting the conveyer and the sewing 110 mechanism and the treadle for the conveyer may be operated independently of the other treadle for starting the conveyer without starting the sewing mechanism.

3. In an apparatus of the character described, a conveyer and means for operating it, a sewing mechanism supported in proper coöperative relation thereto to sew the mouths of sacks supported and carried by said conveyer, clutches for controlling the 115 operation of the sewing mechanism and conveyer, and means for operating said clutches comprising treadles, and connections between said treadles, whereby the movement of the sewing mechanism treadle will operate the conveyer mechanism treadle.

4. In combination with the conveyer, means for operating it, and a treadle controlling the operating means, a sewing mechanism, means for operating it, and a treadle 120

controlling the operating means, said treadles being arranged in proximity to each other, means for connecting them whereby the throwing into operation of the sewing mechanism will operate the conveyer mechanism.

5. In an apparatus for sewing the mouths of filled sacks, a sewing mechanism with means to operate and stop and start it, a 10 conveyer and means to start and stop it, and connections between the stopping and starting means of the sewing machine and the conveyer whereby when the sewing machine is thrown into and out of operation, the conveyer will also be thrown into and out of 15 operation.

6. In an apparatus for sewing the mouths of filled sacks, a sewing mechanism and conveyer, means for operating said sewing 20 mechanism and conveyer, means under the control of the operator to stop and start the conveyer independently of the sewing mechanism, a separate means under the control of the operator to stop and start the sewing mechanism and also to stop and start the conveyer.

7. In an apparatus of the character described, a conveyer and means for operating it, a sewing mechanism supported in 25 proper coöoperative relation thereto to sew the mouths of sacks supported and carried by said conveyer, clutches for controlling the operation of the sewing mechanism and conveyer, and means for operating said 30 clutches comprising treadles, and connec-

tions between said treadles, whereby the movement of the sewing mechanism treadle will operate the conveyer mechanism treadle, said conveyer mechanism treadle being however capable of operation when the sewing mechanism treadle is inactive.

8. In an apparatus of the character described, a driving shaft, a movable clutch connection between the same and the sewing mechanism, and a movable clutch connection between the same and the conveyer mechanism, means under the control of the operator for successively operating said clutches, said means including a treadle lever which successively causes the movement of 50 said clutches.

9. In an apparatus of the character described, a driving shaft, a movable clutch connection between the same and the sewing mechanism, a movable clutch connection between the same and the conveyer mechanism, means under the control of the operator for successively operating said clutches, said means including a treadle lever which successively causes the movement of 55 said clutches, and a second treadle lever which may be also operated independently of the first treadle lever.

In testimony whereof I affix my signature, in presence of two witnesses.

DUDLEY S. SEYMOUR.
